TYPE WHEEL INKING MECHANISM FOR
TOY TYPEWRITERS

Samuel I. Berger, Newark, N. J.

Application January 24, 1947, Serial No. 724,042

8 Claims. (Cl. 197—47)

1

The present invention is concerned with the toy typewriter made the subject of my prior application Serial No. 658,318 filed March 29, 1946, which has issued as Patent No. 2,486,702, dated November 1, 1949, and has for its objects to simplify the construction and to enhance the visibility of the typing area of the platen.

In the accompanying drawings in which is shown one of various possible embodiments of the several features of the invention,

Fig. 1 is a perspective view of the toy typewriter of the present invention showing its general appearance with the simulated keyboard and associated structure in place,

Fig. 2 is a fragmentary view in transverse cross section, taken on line 2—2 of Fig. 1, and

Fig. 3 is a perspective view showing the type wheel and associated bail and inking roller construction.

Since the construction in its general outline follows closely that of the application above identified, only so much of the construction has been shown as is needed to a comprehension of the present improvement and the general description will be correspondingly brief. In general it is noted that the casing structure simulates the general appearance of a modern portable typewriter including, as it does, the base 11, a simulated standard keyboard 12, a housing 13 to the rear thereof, of the shape and dimensions commonly used on standard typewriters to enclose the key lever basket and the ribbon mechanism, and a platen structure 14 to the rear. The housing portion is enlarged at its middle as a hood 15 to enclose the main operating parts of the toy typewriter. The sham keyboard is divided at 20 and a single key lever 21 protrudes therefrom, depression of which effects the typing operation. There is also a spacer lever 22 protruding through the forward part of the housing to operate the spacing escapement (not shown) and not material to the present improvement. The type wheel 23 is mounted on an axle 24 bearing in the side walls of the carriage 28, upon one end of which axle is affixed the indexing wheel 25 which bears on its periphery the same sequence of characters as those of the type about the periphery of the type wheel 23 and serving, in association with the index finger 26 protruding from the hood 15, to set the type wheel for typing a selected character. The actual typing is effected by depression of the key lever 21 which, through link 27 rocks the type wheel mounting carriage 28 about its pivot 29 to bring the selected type into imprinting engagement with the

2

paper 30 on the platen. Spring means (not shown) returns the parts to normal position upon release of the key lever 21.

For inking the type wheel at the characters to be imprinted, an absorbent ink roller 31 is interposed between the type wheel and the platen. That ink roller is mounted on a bail 32, which straddles the type wheel diametrically thereof, with the cross bar 33 thereof at the front of the type wheel or that side thereof remote from the platen, the free ends of the legs of said bail extending toward the platen. The inking roller is mounted between said free ends, preferably by a wire spring holder 34 which has a continuous spring loop 35 and integral generally parallel legs 36 and 37 extending therefrom and readily removable from corresponding slots 38 extending diagonally of the bail legs near the ends thereof. A sleeve 39 about leg 36 mounts the roller 31 and the other leg 37 desirably has a median outturned kink 40 which serves as the pointer to indicate the position of imprint on the paper.

The sheet metal bail 32 is of such width that the distance between its arms is greater than the thickness of the type wheel for adequate clearance and has a pair of tongues 43 cut out from near its ends and from one edge thereof and bent inward, as shown, to extend in close contiguity to the respective edges of the type wheel rim. Thereby lateral displacement of the bail and type wheel relative to each other is precluded and the ink roller always remains in registry with the type to be inked. It will be understood that the inturned tongues 43 could be used adjacent the cross bar of the bail where the latter, as in the copending application above identified, is at the ink roller side of the mechanism.

Preferably the ink roller is normally kept out of contact with the type wheel by a stop post 41 of sheet metal rising from the frame and engaging the sleeve 39. In the typing operation as the carriage 28 is rocked forward, the sleeve 39 disengages stop 41 and the spring holder 34 then brings ink roller 31 into engagement with the type wheel.

Preferably the upper end of the hood 15 has a circular cut-out 42, and in combination with the arrangement of the inking roller bail unobstructed at its inking end by the bail cross bar, affords considerably enhanced visibility of the typed region as contrasted with the construction of my prior application above identified.

As many changes could be made in the above construction and many apparently widely dif-

ferent embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. In a toy typewriter of the character described, a body, a platen at the rear thereof, a type wheel having a horizontal axle, a hood encompassing said type wheel, the axle for said type wheel protruding through said hood, a dialing knob on said axle, an inking roller carrying bail pivotally mounted on said axle and within said hood, the free ends of the bail legs terminating at the platen side of said type wheel, and an inking roller rotatably mounted between said bail legs and adapted to ink the characters about to be imprinted against the platen.

2. In a toy typewriter of the character described, a type wheel having a horizontal axle, a platen, an ink roller interposed between said type wheel and said platen, a carrying bail for said ink roller, said bail straddling said type wheel diametrically thereof, being pivoted on said axle and having its cross bar at the side of said type wheel remote from said platen, said ink roller being mounted between the legs of said bail near the free ends of the latter, and a pointer between said bail legs.

3. In a toy typewriter of the character described, a type wheel having a horizontal axis, a platen, an ink roller interposed between said type wheel and said platen, a carrying bail for said ink roller, said bail straddling said type wheel diametrically thereof, being pivoted on said axle, and having its cross bar at the side of said type wheel remote from said platen, a wire spring holder for said ink roller, extending across the free ends of the legs of said bail and a pointer on said holder between said bail legs resiliently affixed therebetween, and a pointer on said holder between said bail legs.

4. In a toy typewriter of the character described, a type wheel having a horizontal axis, a platen, an ink roller interposed between said type wheel and said platen, a carrying bail for said ink roller, said bail straddling said type wheel diametrically thereof, being pivoted on said axle, and having its cross bar at the side of said type wheel remote from said platen, and a wire spring holder for said ink roller, extending across the free ends of said bail legs and resiliently affixed therebetween, said wire spring holder comprising a spring loop, a leg extending through the roller and mounting the latter, the legs of said bail being slotted to accommodate said spring holder, said spring holder having a second and outer leg with a median kink serving as a pointer.

5. As an article of manufacture, a wire spring holder for the inking roller of a toy typewriter of the character described, said holder comprising a coil spring loop having two generally parallel legs extending therefrom and unitary therewith, one of said legs serving for the mounting of an ink roller, the other of said legs having an outward kink in the middle of its length to serve as a pointer.

6. In a toy typewriter of the character described, a casing having a simulated keyboard, a hood rising therefrom, a type wheel encompassed by said hood and having an axle protruding therefrom, an indexing wheel exposed laterally of said hood and affixed on said axle, an inking bail pivoted on said axle and within said hood, the free ends of the bail legs being exposed at the platen side of said hood, and an inking roller accommodated between said free ends, the hood having a circular cut-out, said cut-out and said bail arrangement contributing to enhanced visibility of the type.

7. In a toy typewriter of the character described, a type wheel having a horizontal axle, a platen, an ink roller interposed between said type wheel and said platen, and a carrying bail for said ink roller, said bail straddling said type wheel, being pivoted on said axle and having side arms spaced by a distance materially greater than the thickness of said type wheel, said arms having cut-out inturned tongues near said ink roller and extending adjacent the respective rim edges of the type wheel, thereby to assure maintenance of the ink roller in alignment with the type on the type wheel.

8. In a toy typewriter of the character described, a type wheel having a horizontal axle, a platen, an ink roller interposed between said type wheel and said platen, and a carrying bail for said ink roller straddling said type wheel diametrically thereof and pivoted on said axle, the distance between the arms of said bail being materially greater than the thickness of said type wheel, said bail being of sheet metal and having tongues cut inward from the edges of the arms thereof and turned inward generally parallel thereto to extend in close contiguity to the respective rim edges of the type wheel and thereby maintain the ink roller substantially in register with the type on the type wheel.
